UNITED STATES PATENT OFFICE.

SAMUEL C. McKEOWN, OF EAST ORANGE, NEW JERSEY, ASSIGNOR TO SPLITDORF ELECTRICAL COMPANY, OF NEWARK, NEW JERSEY.

IGNITION SYSTEM.

1,305,140.

Specification of Letters Patent. Patented May 27, 1919.

Application filed September 9, 1918. Serial No. 253,252.

To all whom it may concern:

Be it known that I, SAMUEL C. McKEOWN, a citizen of the United States, residing at East Orange, in the county of Essex and 5 State of New Jersey, have invented certain new and useful Improvements in Ignition Systems, of which the following is a specification.

My invention relates to ignition systems 10 used in connection with internal combustion engines, more particularly those used in connection with airplanes. Under some conditions of operating the plane, for example, a "nose dive", the spark plugs become 15 fouled, due to oil and possibly other causes so that when the plane is "straightened out" the firing is irregular. The spark plugs may become fouled in regular operation by oil or carbon, so that irregular firing and 20 lost power is encountered, while the plane is in the air.

It has been found that the introduction of 25 an auxiliary spark gap, introduced into the high tension circuit running to the main gaps or spark plugs, while not desirable for continuous running does serve in many cases to clear up fouled plug gaps, probably due to the fact that the auxiliary spark gap greatly reduces the secondary current so that 30 the voltage can build up in more or less oscillatory waves to a much higher point than in ordinary operation, which voltage is sufficient to produce a spark across the fouled gap and continued explosions will then 35 many times remove the source of trouble.

It is the principal object of my invention to provide an auxiliary spark gap which can be introduced into the high tension circuit at the will of the operator of the engine on 40 which my ignition system is used. Another object of my invention is to provide automatic means for returning this auxiliary spark gap to a normal closed or operating position when its use is not desired. An 45 other object is to provide the necessary safety devices for the generating coil under all conditions of operation. A still further object of my invention is to provide a mechanism for accomplishing the work as previously set forth in a simple, inexpensive but reliable manner. Other and further objects will be apparent to one skilled in the art after a study of this specification taken in connection with the annexed drawings, wherein— 50

55 Figure 1 illustrates an ignition device of

the magneto type, to which I have applied the principles of my invention, one of the cover plates being partly broken away.

Fig. 2 is a part sectional and part plan view on the line 2—2 of Fig. 1. 60

Fig. 3 is similar to Fig. 2, but with certain parts moved in a different position.

Fig. 4 is an end view of the generating coil shown in Fig. 1 with one of the heads removed. 65

Fig. 5 is an end view of the socket member shown on the left hand cover plate of Figs. 2 and 3.

Referring now to the details, wherein like numbers refer to corresponding parts in the 70 various views, 1 is an ignition generator of the magneto type having magnets 2 and 3 and the distributor block 4 mounted on the end plate 5. The magneto shown is of the Dixie type having relatively stationary field 75 poles 6, one of which is shown in Fig. 1. Fastened to the field pole 6 by yokes 41 is a coil structure 8, having heads 9 and 10 between which and around the core 7 the usual primary and secondary windings are assembled. Between the heads 9 and 10 on one side is a high tension terminal block 11, 80 having a distributor finger contact 12 on which a brush 13 operates. The brush 13 is carried by a distributor finger supported by 85 insulator 15, passing through the magnets 2 and 3 into the interior of the distributor block 4 where the current is distributed to the various distributor contacts in the usual way. Only one cable 16 is shown running 90 from the block to a spark gap 17, which may be taken to illustrate a spark plug in an engine cylinder. The block 11 also carries a main safety gap electrode 18 and an auxiliary spark gap contact 19. A ground electrode 20 is carried on the coil head 9 so that the gap between 18 and 20 form, what I term, the main safety gap, M. S. G. 95

On the opposite side of the coil structure from block 11, the block 21 is fastened to the 100 heads 9 and 10. The block 21 carries an auxiliary safety gap plate 22 to which the outer end of the high tension winding is connected as at 23. The coil heads 9 and 10 also carry a member 24, which, in the 105 form shown, is rectangular in shape and which is adapted to slide freely through suitable openings in the heads. Member 24 carries a plate 25, which I term an auxiliary gap plate, which is preferably slotted at 26 110

to produce a resilient finger 27 normally held in engagement with contact 19. Member 24 also carries a resilient device such as a spring 28, the bottom of which rests on the body portion 29 of member 22 and the top of the brush engages plate 25, so that the high tension winding is continually in contact with the plate 25.

The outer end of the movable member 24, 10 which is preferably of insulating material, has an insert 30 set therein. A transverse hole 31 and a slot 32 passes through both member 24 and the insert 30 to securely hold in position a ball 33 that is securely fastened 15 to a Bowden wire cable 34, which is incased in a flexible protecting tubing 35. The socket member 36 is fastened to the side cover 37 in a suitable manner, as by screws 38. Socket 36 carries a cup shaped member 39, which with the socket 36 supports a resilient member 40. The cable 34 with its 20 protecting sheath 35 extends to within reach of the operator or pilot of the airplane, who by means of a suitable handle can apply 25 pulling force to the cable 34 at will.

When it is desired to introduce the auxiliary spark gap which I designate as A. S. G. a pull applied to cable 34, which from the description heretofore given, causes finger 27 30 to leave the contact 19, introducing the A. S. G. into the high tension circuit. After the A. S. G. is started into operation the strain on the high tension winding of the generating coil might become so severe as to break 35 it down, since the combined distance of the A. S. G. and the main safety gap, which I designated M. S. G., is much greater than M. S. G. alone. I therefore preferably construct the auxiliary spark gap plate 25 so 40 that predetermined gaps of different lengths are obtained by means of the serrations 42. When the plate 25 has been moved to the extreme position to the left, as shown in Fig. 3, the A. S. G. is preferably 5 mm. on the machine shown; the M. S. G. usually about 9 $\frac{1}{2}$ mm., which gives a total gap of 14 $\frac{1}{2}$ mm. on 45 the high tension winding, should one of the spark plug wires fall off. I, therefore, consider it advisable, although not absolutely necessary, to substitute for the M. S. G. an auxiliary safety gap which I designate A. S. of approximately 12 mm. which will both 50 protect the high tension coil winding as well as to allow for the increased potential to act in the manner heretofore described. It will 55 be apparent that when the operator ceases to pull on the cable 34 that the spring 40 which has been compressed as shown in Fig. 3, will return automatically, the member 24 60 with plate 25 to a normal position shown in Fig. 2.

While I have shown and described the application of my invention to a magneto of the Dixie type, it will be apparent that the 65 same may be applied to other types of mag-

netos as well as to a battery ignition system, and I, therefore do not wish to be limited to the exact details herein shown and described.

Having thus described my invention what I claim is:—

1. In an ignition system, a high tension circuit having a main spark gap therein for firing fuel and a second spark gap in said circuit for adding to the effectiveness of the 75 sparking at the first mentioned gap, said second spark gap being automatically held in normal closed position but constructed and arranged to be introduced when desired.

2. In an ignition system, a high tension circuit having a main spark gap therein for 80 firing fuel and a second spark gap in said circuit for adding to the effectiveness of the spark at the first mentioned gap, said second spark gap being automatically held in normal 85 closed position but constructed and arranged to be introduced in variable lengths at will.

3. In an ignition system, a high tension circuit having a main spark gap therein for 90 firing fuel and a second spark gap in said circuit for adding to the effectiveness of the spark at the first gap when the same is 95 "fouled", said second spark gap being normally short circuited by a member constructed and arranged to be moved so as to introduce at will predetermined gaps of different lengths as desired.

4. In an ignition system, a high tension circuit having a main spark gap therein for 100 firing fuel and a second spark gap in said circuit for adding to the effectiveness of the spark at the first gap when the same is 105 "fouled", said second spark gap being normally short circuited by a member constructed and arranged to be manually moved 110 so as to introduce said gap at will, and means for automatically restoring the short circuit around the second gap when the manual force is removed.

5. In an ignition system a high tension 110 circuit having a main spark gap therein for firing fuel and a second spark gap in said circuit for adding to the effectiveness of the spark at the first gap when the same is 115 "fouled", said second spark gap being normally short circuited by a member constructed and arranged to be manually moved so as to introduce said gap at will, means for automatically restoring the short circuit around the second gap when the manual 120 force is removed, a main safety gap for the said circuit and an auxiliary safety gap therefor brought into operative condition by the introduction of said second spark gap.

6. In an ignition system, a generating coil having a high tension winding connected in circuit with a main spark gap for firing fuel, a main safety gap for said winding, an auxiliary spark gap, an auxiliary safety 125 gap,

- gap and manually operable means for introducing the auxiliary spark gap into the high tension circuit and substituting the auxiliary safety gap for the main safety gap as described.

7. In an ignition system, a generating coil structure having a high tension winding connected in circuit with a main spark gap for firing fuel, a main safety gap for the high tension winding carried on the coil structure, an auxiliary spark gap carried on a member supported by the coil structure and manually operable means connected to said member for moving the same to introduce said auxiliary spark gap into circuit with the main spark gap as described.

8. In an ignition system, a generating coil structure having a high tension winding connected in circuit with a main spark gap for firing fuel, main and auxiliary safety gaps for the high tension winding carried on the coil structure, an auxiliary spark gap carried on a member supported adjacent to the high tension winding and manually operable means connected to said member for moving the same to introduce said auxiliary spark gap into circuit with the main spark gap and to substitute the auxiliary safety gap for the main safety gap.

9. In an ignition system, a generating coil structure having a high tension winding connected in circuit with a main spark gap for firing fuel, a main safety gap for the high tension winding carried in a relatively fixed position on the coil structure, a movable member carried by the coil structure, an auxiliary spark gap plate carried on the movable member permanently connected into the high tension circuit but normally closing the auxiliary spark gap, manually controlled means for operating the movable member to introduce the auxiliary spark gap and means for restoring the movable member and plate to normal position when the auxiliary spark gap is no longer desired.

10. In an ignition system, a generating coil structure having a high tension winding connected in circuit with a main spark gap for firing fuel, a housing for said coil structure; said coil structure carrying the following instrumentalities: a high tension terminal block having a distributing finger contact, a main safety gap electrode and an auxiliary spark gap contact, a ground electrode for the main safety gap, an auxiliary

safety gap plate connected to the high tension winding; a movable member carrying an auxiliary spark gap plate with connecting means between the auxiliary safety gap plate and said spark gap plate; and means fastened to a part of the said housing for holding said movable member in such a position that the auxiliary spark gap plate is normally in contact with the auxiliary spark gap contact, said means being operable to move the movable member and spark gap plate to introduce an auxiliary spark gap in the high tension circuit and substitute an auxiliary safety gap for the main safety gap for the purpose described.

11. In an ignition system, a generating coil structure having a high tension winding connected in circuit with a main spark gap for firing fuel, and mechanism carried by said coil structure for introducing an auxiliary spark gap into circuit with the main spark gap, for the purpose described.

12. In an ignition system, a generating coil structure having a high tension winding connected in circuit with a main spark gap for firing fuel, and mechanism carried by said coil structure for introducing predetermined gaps of different lengths into circuit with the main spark gap.

13. In an ignition system, a high tension circuit having a main spark gap therein for firing fuel and means for introducing an auxiliary spark gap into the high tension circuit at a point closely adjacent the origin of the high tension current for the purpose described.

14. In an ignition system, a high tension circuit having a main spark gap therein for firing fuel, a main safety gap for said circuit and means for introducing an auxiliary spark gap into the high tension circuit and substituting an auxiliary safety gap for the main safety gap at a point closely adjacent the origin of the high tension current for the purpose described.

15. In an ignition system, a high tension circuit having a main spark gap therein for firing fuel, manually operable means for introducing an auxiliary spark gap into said circuit at a point closely adjacent the origin of the high tension current and automatic means for closing the auxiliary spark gap when the manual force is removed.

In witness whereof I affix my signature.

SAMUEL C. McKEOWN.
